(57) **CLAIM**

The ornamental design for a handset, as shown and described.

DESCRIPTION

FIG. 1 is a perspective front view of a handset showing our new design;

FIG. 2 is a perspective rear view thereof;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof.

The broken lines immediately adjacent the shaded areas, encompassing unshaded regions, represent the bounds of the claimed design while all other broken lines are directed to environment and are for illustrative purposes only; the broken lines form no part of the claimed design.

The contrast in shading in the figures represent a contrast in appearance.
